UNITED STATES PATENT OFFICE

RANDHIR SINGH KHAIRA, OF NAVASOTA, TEXAS

PHONOGRAPH

Application filed January 5, 1928. Serial No. 244,668.

The present invention relates to improvements in phonographs and has for its principal object to provide an improved turn table and record disc construction whereby the 5 stylus will be prevented from scratching the record disc after the reproducer carrying the stylus has traversed the face of the record disc.

Another important object of the invention 10 is to provide a phonograph wherein the record disc is removably supported on the turn table, the securing means being of such construction as to prevent any possibility of the record disc slipping or otherwise moving on 15 the turn table when placed thereon.

A further object is to provide a phonograph wherein the same is electrically operated. means being provided for automatically stopping the motor that controls the operation of 20 the turn table carrying armature shaft when the record has been played and the reproducer is disposed within a centrally located cavity former in the face of the record disc.

A still further object is to provide a phonograph of the above mentioned character 25 which is simple in construction, inexpensive, strong and durable and further well adapted to the purpose for which it is designed.

Other objects and advantages of the invention 30 will become apparent from the following description when taken in connection with the accompanying drawings.

In the accompanying drawings forming part of this application and wherein like reference characters indicate like parts:

Figure 1 is a sectional view through the turn table and the record disc supported thereon, the phonograph casing being shown in such a manner as to illustrate the position 40 of the operating mechanism for the turn table.

Figure 2 is a fragmentary top plan view 45 showing the reproducer disposed within the central cavity formed in the record disc after the stylus has traversed the record disc, and further illustrating the automatic cut off for the motor.

Figure 3 is a sectional view through the inner end of the tone arm and the supporting 50 means therefor, and also showing the man-

ner in which the record disc is supported on the rotatable turn table.

Figure 4 is a top plan view of the turn table. Figure 5 is a similar view of my improved record disc.

Figure 6 is a detail elevational view of the outer end of the tone arm showing the reproducer supported thereon, and

Figure 7 is a sectional view taken substantially on the line 7—7 of Figure 6.

In the drawings wherein for the purpose of illustration is shown the preferred embodiment of my invention, the numeral 1 designates the casing, the same having arranged therein an induction motor for any conventional construction and which is designated generally by the numeral 2. The elongated armature shaft 3 that is associated with this motor extends upwardly in the casing, and the upper end extends through a suitable 70 opening provided therefor in the top of the casing as shown more clearly in Figure 1. A plate 4 is secured to the bottom face of the top of the casing around the aforementioned opening for steadyng the armature shaft, 75 and additional bracing means for the armature shaft is shown at 5.

Forming a salient part of the present invention is the turn table 6, the same being formed with a central depression or socket 7 80 in the upper face thereof, as more clearly shown in Figures 3 and 4 of the drawings. This turn table is secured on the plate-like head 8 arranged on the upper end of the armature shaft 3 by a screw such as is shown 85 at 9, and which screw extends centrally through the turn table. The purpose of the socket or depression 7 will be hereinafter more fully described.

A pair of diametrically opposed pins 10 90 extend upwardly from the upper face of the turn table 6 adjacent the perimeter thereof, and the purpose of these pins will also be presently apparent.

The invention further comprehends the 95 provision of an improved record disc and to this end, the disc 11 is provided with an enlarged central hole indicated at 13. The upper and bottom faces of the record disc have formed therein the usual sound grooves 100

14 and the same extend from a point inwardly of the peripheral edge of the disc to the edge of the central hole 13, the sound grooves having communication with the hole as indicated in Figures 2 and 5 of the drawings.

The peripheral edge portion 15 of the record disc 11 that does not have the sound grooves formed therein is provided at equidistantly spaced points with the openings 16. In the present instance four of such openings are provided, and these openings cooperate with the upstanding pins 10 for securing the record disc 11 on the turn table so that said disc will not slip or otherwise move on the turn table when properly positioned thereon. By providing four of such openings 16, it will be readily obvious that should the record be broken at its edge 20 where one of the openings is formed, the other pair of diametrically opposed openings may be used to permit the securing of the record disc on the turn table in a positive manner.

Furthermore, when the record disc is secured on the upper face of the turn table, the central opening 13 that is of the same diameter as the socket or depression 7 will be in alignment with the socket formed in the upper face of the turn table and this is clearly shown in Figures 1 and 3 of the drawings.

The record disc is of a smaller diameter than the turn table, and the edge portion of the turn table that extends beyond the outer edge of the record disc is formed with the notches 12 as shown in Figure 4 for the purpose of permitting the fingers to easily engage under the adjacent edge portion of the record disc and facilitate the removal of said disc.

Extending upwardly from the top of the casing 1 and adapted for communication with the horn (not shown) that may be arranged within the casing at any appropriate manner is the throat 17. The lower end of this throat is formed with an annular flange 18 that rests on the upper face of the top of the casing in the manner shown very clearly in Figure 3. This throat is formed with the spaced annular ribs 19 on the outer face thereof and these ribs cooperate with the annular channels 20 formed in a sleeve 21 that fits over the upper portion of the throat 17 whereby the sleeve is capable of rotation on the throat. The upper end of the sleeve 21 is reduced to form a neck portion 22.

A tone arm 23 is secured at its inner end within the neck portion 22 in a rigid manner so that said tone arm will rotate with the sleeve 21 about the throat 17.

The outer end of the tone arm 23 is disposed laterally as illustrated at 24 and carried by this portion of the tone arm is the reproducer designated generally by the numeral 25, the same being provided with the

sleeve 26 to fit over the laterally extending outer end portion 24 of the tone arm. This sleeve 26 is formed with a pair of spaced annular channels 27 similar to the channels formed in the sleeve 21 and adapted for cooperation with these channels are similar shaped ribs formed on the laterally extending portion 24 of the tone arm.

The sleeve 26 is frictionally engaged with the laterally extending outer end 24 of the tone arm, yet is capable of being turned in an upward and downward direction for facilitating the disposition of the stylus 28 in an operative or inoperative position. A pin and slot arrangement is associated with the laterally extending outer end 24, and the sleeve 26 of the reproducer for limiting the rotation of the sleeve on the outer end portion of the tone arm, and this pin and slot construction is illustrated at 29 and 30, respectively.

A socket 31 is arranged in the side of the casing and is electrically connected to a suitable source of supply by the wires 32 and 33. The motor 2 is electrically connected to the socket by the wiring as shown in Figure 1. For the purpose of starting and stopping the motor, there is provided both a manually operated means as well as an automatic mechanism. The manually controlled mechanism includes the provision of a rheostat 34 within the casing and cooperating with the rheostat is the manually operable lever 35 that projects beyond the adjacent side of the casing. A contact element 36 is associated with this lever for cooperation with the rheostat in the manner well known in the art whereby the speed of the motor may be controlled, and furthermore when the lever is in one position, the current to the motor will be cut off.

The automatic mechanism for starting and stopping the motor comprises the provision of an annular ring 37 of any suitable insulating material. This ring encircles the lower portion of the throat 17 and is secured on the flange portion 18 in any appropriate manner. A portion of the insulating ring is cut out and secured within the cut out portion is the segmental contact 38 and adapted for cooperation with this contact is the brush 39 carried by the rotatable sleeve 21 that is associated with the tone arm 23. The brush and segmental contact are electrically connected to the motor and source of supply by the wiring shown in Figure 1.

In operation, a record disc of the type shown in Figure 5 is secured on the turn table 6 and the tone arm is disposed adjacent the outer edge of the disc so that the stylus is in engagement with the outer most record groove 14 formed in the upper face of the record disc. When the parts are so arranged, the brush 39 will be in engagement with one end of the segmental contact strip 38 and the motor will thus be actuated to effect the ro-

tation of the turn table and the record disc supported thereon.

When the stylus 28 has completely traversed the upper face of the record disc, and the same reaches the innermost sound groove, by reason of said innermost sound groove communicating with the hole in the record, the stylus will enter the hole and the underlying socket formed in the turn table and thus prevent the further contact of the stylus with the upper face of the record disc. Simultaneously, the brush 39 will have passed beyond the other end of the contact strip 38 and reach or touch the insulating ring 37 thereby cutting off the current to the motor, and thus stopping the rotation of the turn table and the record disc supported thereon.

When the reproducer 25 is disposed in the position shown in Figures 2 and 3 of the drawings, the stylus cannot contact with the upper face of the record disc, and therefore the stylus will not be made blunt such as frequently results when a phonograph of the conventional construction and which employs the usual type of record disc is not stopped at the proper time.

The provision of a phonograph of the above mentioned character will insure the securing of the record disc in a positive manner on the turn table so that there will be no possibility of the record disc slipping or otherwise moving independently of the turn table and thereby the pitch of the notes emitted from the phonograph will in no way be affected. This will permit the phonograph to reproduce the voice in a clear manner.

While I have shown the preferred embodiment of my invention, it is to be understood that various changes in the size, shape and arrangement of parts may be resorted to without departing from the spirit of the invention and the scope of the appended claims.

Having thus described the invention, what I claim as new and desire to secure by Letters Patent is:—

1. In a phonograph, the combination of a rotatable turn table having a central depression formed in the upper face thereof, and a record disc removably secured on the turn table and having a central hole for receiving the stylus of a phonograph reproducer after the stylus of the reproducer has traversed the record disc.

2. In a phonograph, the combination of a turn table, a record disc provided with spaced openings in the outer edge portion thereof, and pins extending upwardly from the turn table for disposition through the respective openings for preventing movement of the record disc on the turn table.

3. In combination, a phonograph turn table, a record disc provided with spaced openings in the outer edge portion thereof, upstanding pins carried by the turn table

for disposition through the respective openings to secure the record disc on said turn table, said record disc being formed with a central hole, and sound grooves in the faces thereof, the innermost groove on each face communicating with the hole in the disc for the purpose described. 70

4. In combination, a phonograph turn table having a central depression formed in the top face thereof, a record disc formed with a series of spaced openings in the outer edge portion thereof, pins extending upwardly from the turn table for disposition within the respective openings to secure the disc on the turn table, the central portion of the disc being formed with an enlarged hole adapted for registration with the central depression formed in the upper face of the turn table for the purpose described. 75

5. In a phonograph, the combination of a casing, a rotatable turn table, an electric motor for actuating the same, a record disc for disposition upon the turn table, and a throat, a tone arm swivelly mounted at its inner end on the throat, a reproduced unit carried by 80 the outer end of the tone arm, an electric circuit for the motor, and a switch structure arranged within the circuit and associated with the throat and the adjacent portion of the tone arm for normally closing the circuit to 85 the motor during the movement of the reproducer unit across the record disc, the circuit being broken to the motor when said reproducer unit reaches the innermost sound groove in the record disc, said switch structure including an insulating ring encircling the throat, a segmental contact strip carried by the upper face of said insulating ring, and a brush carried by the tone arm for engagement with the upper face of the insulating 90 ring and the contact strip. 95

In testimony whereof I affix my signature.

RANDHIR SINGH KHAIRA.
